CLAMPING DEVICE

Clyde M. Rutter, Massillon, Ohio, assignor to Republic Steel Corporation, Youngstown, Ohio, a corporation of New Jersey

Application August 10, 1932, Serial No. 628,207

1 Claim. (Cl. 51—217)

This invention relates to the art of surfacing metal sheets by grinding. It relates more specifically to a clamping device for securing the metal sheets to a reciprocable table during the grinding operation.

Heretofore in grinding metal sheets, particularly stainless steel sheets, taking a high polish, the devices for holding the sheets were cumbersome and awkward to use and of such a nature that quick and easy adjustment thereof was impossible, thus adding to production cost by way of time lost on finishing the pieces and by way of time lost in securing the pieces to the table. For example, specially constructed hooks were employed which called for the piercing of the sheets, resulting in considerable scrap loss, not to mention the tendency on the part of the sheet to buckle during the grinding operation, resulting in a relatively high percentage of loss from this source. The sheets were also held by means of bolted clamps. However, the adjustment and tightening of the clamps took considerable time and effort which did not lend itself to economical production. Ordinarily, the clamping devices were placed at the ends of the sheet and would often interfere with the grinding wheel if the table were given a full stroke. Hence, the end zone of each sheet remained unfinished and constituted so much scrap loss.

This invention comprehends a manually operable clamping device having a portion for engaging the work and a lever for operating said portion. The portion which engages the work is adapted to grip the sheet in that zone which travels back and forth beneath the grinding wheel. To prevent interference with the grinding wheel, the upper surface of the part is arcuately contoured and struck on a slightly greater radius than the grinding wheel which will allow the part to travel under the grinding wheel a limited distance, determined by the clearance between the wheel and the sheet, which will allow a full stroke of the table without the clamping means and grinding wheel interfering.

One object of this invention is to provide a manually operable device for clamping the end of a sheet to be ground that will permit the sheet to be readily and easily grasped and securely held during the grinding operation. Another object of this invention is to overcome scrap loss at the ends of the sheets by permitting of a full stroke of the table. Still another object of this invention is to provide a clamping means that will not interfere with the grinding wheel during reciprocation of the table.

Other objects and advantageous features of this invention will be observed in the following detailed description, reference being had to the accompanying drawing wherein like characters of reference designate corresponding parts and 5 wherein:

Figure 1 is a fragmentary elevation illustrating our invention in conjunction with the grinding wheel of a polishing table.

Figure 2 is a perspective view of the clamp, 10 and

Figure 3 is a fragmentary perspective view of the base plate which is carried by the reciprocating table.

Referring now to the drawing and particularly 15 Figure 1 there is illustrated a grinding wheel A, a reciprocating table of a sheet grinding machine B and the clamping means C. The table B is adapted to have secured thereto in any suitable manner a base plate 1 in which is formed 20 a laterally extending T-slot 2. The formed end of the base plate is preferably notched as at 3 to receive the end of a rider sheet 4 upon which is disposed a sheet of linoleum 5 or other fibrous material acting as a cushion for the metal sheet 25 during the grinding operation. Both the rider sheet and the covering of linoleum are secured to the base plates in the notched portion thereof through the medium of bolts 6. Disposed on the upper surface of the linoleum is the metallic 30 sheet to be polished, one end thereof being securely clamped to the base plate by means of my novel clamp C.

The clamp C (Figure 2) comprises a rocker arm 7 mounted for pivotal movement about a 35 transverse axis, one end thereof having a serrated surface 8 adapted to contact with the end of the sheet and to compress the end thereof to the base plate of the table. The top surface of the rocker arm 7 in the zone ahead of the axis 40 is provided with an arcuate surface of complementary configuration with the surface of the grinding wheel thereby permitting the grinding wheel to approach as near the end of the sheet as is possible on one hand and to permit the 45 rocker arm to travel under the grinding wheel a maximum distance. The radius of the arcuate face of the rocker arm 7 depends in the main on the radius of the grinding wheel. For instance, the radius R' struck from the center of the grinding wheel may be slightly less than the radius R² which designates the radius of the top surface of the rocker arm. It will be appreciated that this method of determining the radius will give the rocker arm a maximum stroke without inter- 50 55

ference with the wheel and will allow the nose to approach close to the vertical axis of the wheel. The rocker arm 7 intermediate the ends thereof is pivoted to a block 10 as hereinbefore mentioned, the block having outwardly extending footers 9 which are adapted to slidably engage the T-slot 2 of the base plate whereby the clamp may be adjusted laterally of the grinding wheel so as to be adaptable to sheets of varying widths.

10 The opposite end of the lever arm 7 is preferably bifurcated as at 11 to receive a cam element 12 which has a handle 13 that may be readily grasped by the operator. When the block is engaging the T-slot of the base member the surface of the cam member 12 is adapted to co-act with the surface of the base plate so that any movement of the handle 13 will raise or lower the end of the rocker arm 7 thereby clamping a sheet in position or releasing the sheet from the 20 table.

15 Although I have shown the rocker arm with an arcuate upper side, it will be appreciated that the arm may be wedge shaped in this zone or may take any one of a number of shapes that 25 will give the desired result, namely that of grasping the sheet in such a manner that a full stroke of the table will be permitted without interfering with the grinding wheel.

20 Although the foregoing description is neces-

sarily of a detailed character in order to set forth this invention it is to be understood that the specific terminology is not intended to be restrictive or confining and it is further understood that various rearrangements of parts and 5 modifications of structural detail may be resorted to without departing from the scope or spirit of this invention as herein claimed.

We claim:

In apparatus for grinding metal sheets and the like, the combination of a grinding wheel, a reciprocating table for presenting a metal sheet to the grinding wheel, said table being provided with a notched portion along one edge to receive the edge of a sheet to be ground and a slot extending transversely of the table and spaced from the notched portion, and means for clamping the sheet in the notched portion of the table comprising a bearing block slidably mounted in said slot, a lever arm pivoted on said bearing block 20 having a nose portion cooperating with the notched portion of the table and a hand actuated cam element secured thereto remote from said nose portion, said cam element, when actuated, operating to raise the end of the lever arm and 25 bring the nose portion into clamping relation with said table and frictionally lock the bearing block against movement within the slot.
